ANTISEPTIC DETERGENT COMPOSITIONS
 Kurt Moedritzer, Webster Groves, Mo., assignor to
 Monsanto Company, a corporation of Delaware
 No Drawing. Filed Dec. 23, 1963, Ser. No. 332,945
 11 Claims. (Cl. 252—107)

This invention relates to new and novel detergent compositions and more particularly to detergent compositions containing a bacteriostatic agent.

Detergents of themselves are not effective in preventing or arresting the growth or action of microorganisms such as the Staphylococci, i.e., *Staphylococcus aureous*, either by inhibiting their activity or by destroying them. Thus, when such action is desired bacteriostatic agents must be incorporated into the detergent composition to fulfill this function. However, none of the known bacteriostatic agents which are effective in the presence of detergent compositions aid in the cleansing action and, in fact, some are deleterious to such action. As can be appreciated, therefore, a bacteriostatic agent which also exhibits surface active properties and thereby aids the detergent in the cleansing action would represent an advancement in this art.

It is, therefore, an object of this invention to provide improved antiseptic detergent compositions.

It is a further object of this invention to provide detergent compositions having incorporated therein a bacteriostatic agent which exhibits surface active properties.

Other objects will become apparent from a reading of the following detailed description and the claims appended hereto.

It has been found that quaternary phosphonium halides of the following formula

wherein R_1 is an aliphatic group containing 6 or more carbon atoms; R_2 , R_3 and R_4 are members selected from the group consisting of aliphatic groups, aryl groups, alkaryl groups, aralkyl groups and alicyclic groups of from 1 to 12 carbon atoms; and X is a member selected from the group consisting of chlorine, bromine and iodine ions, unexpectedly exhibit bacteriostatic properties as well as surface active properties as will be more fully discussed hereinafter.

In the foregoing general Formula 1 wherein R_1 represents an aliphatic group containing 6 or more carbon atoms, it is preferred that the group contain not over about 24 carbon atoms and the group may be a straight chain structure or branched chain structure and may be a saturated group as well as an unsaturated group containing both double and triple bonds, although it is preferred that the group be either an alkyl group or an ethylenically unsaturated group with the group containing from about 8 to 18 carbon atoms. When the symbols R_2 , R_3 and R_4 represent groups containing carbon chains, such as aliphatic groups, or groups containing alkyl moieties, i.e., alkaryl groups, such carbon chains may be a straight or branched chain structure. When the symbols R_2 , R_3 and R_4 represent groups containing unsaturated carbon chains, these chains may contain both double bonds and triple bonds as well as contain more than one of such bonds although it is preferred that when such symbols represent unsaturated carbon chains they are mono-ethylenically unsaturated. When the symbols R_2 , R_3 and R_4 represent groups containing aromatic carbon rings such as aryl groups or groups containing aryl moieties, i.e., alkaryl groups, such carbon rings are preferably mono- or di-ring

2

groups with the mono-ring group being especially preferred. Although the groups represented by R_2 , R_3 and R_4 , may be like or unlike, it is preferred that each of the groups contain not over about 8 carbon atoms. In addition, all of the groups represented by R_1 , R_2 , R_3 and R_4 may contain one or more of the following substituents: hydroxy groups, amino groups, amide groups, ester groups, sulfonyl groups, sulfo groups and nitro groups.

It has been found that the unsymmetrical tetraalkyl phosphonium halides of the following formula:

wherein R_1 is an alkyl group containing from about 8 to 18 carbon atoms; R_2 , R_3 and R_4 are lower alkyl groups (1-5 carbon atoms) and X is a member selected from the group consisting of bromine and chlorine ions, are particularly effective and especially preferred bacteriostatic agents as well as surface active agents.

Such compounds include:

- 25 (1) trimethyl dodecyl phosphonium chloride
- (2) triethyl octylphosphonium bromide
- (3) trimethyl tetradecyl phosphonium chloride
- (4) tri-n-propyl octadecyl phosphonium bromide
- (5) tri-n-amyl decyl phosphonium chloride
- (6) triethyl decyl phosphonium chloride
- (7) trimethyl decyl phosphonium bromide
- (8) triethyl dodecyl phosphonium chloride
- (9) tri-isopropyl tetradecyl phosphonium bromide
- (10) tri-n-butyl decyl phosphonium chloride

30 Examples of compounds other than of the preferred class described above which can be employed in accordance with this invention include:

- (1) triphenyl oleylphosphonium chloride
- (2) triethyl heptene-1 phosphonium chloride
- 35 (3) tricyclopentyl dodecylphosphonium chloride
- (4) tricyclohexyl tetradecylphosphonium bromide
- (5) tricyclohexyl decylphosphonium bromide
- (6) triphenyl hexadiene-1,5-phosphonium iodide
- (7) tribenzyl tetradecylphosphonium bromide
- 40 (8) tribenzyl dodecylphosphonium chloride
- (9) tri-isoamyl oleylphosphonium iodide
- (10) tri-isopropenyl decylphosphonium bromide
- (11) tri-p-tolyl heptene-1-phosphonium iodide
- (12) tri-p-tolyl decylphosphonium chloride
- 45 (13) trixylyl tetradecylphosphonium bromide
- (14) tri-isobutetyl tetradecylphosphonium chloride
- (15) tripropenyl tetradecylphosphonium iodide
- (16) tri-n-butenyl decylphosphonium iodide
- (17) tri-isopropenyl hexadecylphosphonium iodide
- 50 (18) triphenyl tetradecylphosphonium bromide
- (19) tribenzyl octylphosphonium chloride
- (20) tricyclohexyl octadecylphosphonium bromide

60 The quaternary phosphonium halides of the present invention can be prepared by many various methods which include reacting in an inert atmosphere a triorgano phosphine with an aliphatic halide at temperatures of from about 100° C. to about 180° C. for a period of a few hours. The following is the reaction in equation form:

70 wherein the groups R_1 , R_2 , R_3 , R_4 and X are the same as represented in the foregoing general Formula 1.

The following examples are presented to illustrate the invention, with parts by weight being used in the examples unless otherwise indicated.

Example 1

Into a reaction vessel are charged about 202 parts of tributyl phosphine and about 249 parts of dodecyl bromide under nitrogen. The reaction mixture is heated to about 150° C. for about 4 hours yielding tributyl dodecyl phosphonium bromide, a waxy solid (M.P. 33° C.) in nearly quantitative yields.

Example 2

In the same manner as indicated in Example 1, about 202 parts of tributyl phosphine and about 205 parts of dodecylchloride were reacted to yield tributyl dodecyl phosphonium chloride, a viscous liquid.

Example 3

In the same manner as indicated in Example 1, about 202 parts of tributyl phosphine and about 273 parts of tetradecyl bromide were reacted to yield tributyl tetradecyl phosphonium bromide, a waxy solid (M.P. 37° C.).

Example 4

In the same manner as indicated in Example 1, about 202 parts of tributyl phosphine and about 297 parts of hexadecyl bromide were reacted to yield tributyl hexadecyl phosphonium bromide, a waxy solid (M.P. 55° C.).

Example 5

In the same manner as indicated in Example 1, about 202 parts of tributyl phosphine and about 321 parts of octadecyl bromide were reacted to yield tributyl octadecyl phosphonium bromide, a waxy solid (M.P. 65° C.).

Example 6

In the same manner as indicated in Example 1, about 7.6 parts of trimethyl phosphine and about 25 parts of dodecyl bromide were reacted to yield trimethyl dodecyl phosphonium bromide, a white solid (M.P. 193° C.).

The term "detergent" includes soap, i.e., an alkali metal or amine salt of a fatty acid and/or fatty acid mixture, and synthetic detergents, particularly of the anionic, non-ionic and amphoteric classes, including mixtures of these. The term "antiseptic detergent composition" refers to those detergent compositions which are satisfactory detergents and which are effective against *Staphylococci*.

The quaternary phosphonium halides of the present invention have been found to not only exhibit surface-tension-reducing properties in aqueous systems but also to exhibit effective bacteriostatic properties in such systems in the presence of detergent compositions. In general, quaternary phosphonium chlorides are normally liquids while the bromides are normally solids which permit versatile yet selective methods for formulating with detergent compositions. In addition, these bacteriostatic agents neither discolor the finished detergent composition nor are irritating to the skin. It is, of course, a distinct advantage of the bacteriostatic agents of the present invention that they additionally aid the detergent composition in its cleansing action by exhibiting surface active properties in aqueous systems.

The amounts of the quaternary phosphonium halides which are suitable for use in detergent compositions can vary depending upon the end use applications of the detergent composition, such as bar soap, hair shampoo and the like, and, in general, any amount which is antiseptically effective, i.e., effective against *Staphylococcus*, can be used with amounts below about 50% by weight of the detergent composition being usually acceptable and amounts from about .05% to 10% being preferred. Under some circumstances, some bacteriostatic activity can be found as low as .001% by weight of the detergent.

The invention is not to be limited to any particular method of preparing the detergent composition contain-

ing the bacteriostatic agent. The bacteriostatic agent can be mechanically mixed in, crutched in the detergent in the form of a slurry, or dissolved in a solution of the detergent. In addition, the bacteriostatic agent can be admixed with the detergent in any of the forms in which the detergent is manufactured in, as well as being added simultaneously or separately to an aqueous solution. In any event, the bacteriostatic agent is intended to be used with the detergent at the time of application as a cleansing agent.

The resulting antiseptic detergent composition, that is, the detergent and the bacteriostatic agent, of the present invention is generally effective when used in aqueous systems in conventional amounts such as is normally used with detergent compositions and which is generally about .2% concentration or below.

In order to illustrate the surface active properties of the bacteriostatic agents of the instant invention, the following table presents the surface tensions in dynes per centimeter of solutions at the indicated concentrations of these agents and distilled water at 25° C. as determined by the DuNuoy principle using the Fisher tensiometer. The surface tension of water is about 72.8 degrees/cm. at this temperature. A reduction of the surface tension of water to about 30 dynes in .25% solution is considered excellent and if this reduction is maintained practically unchanged to a dilution as low as .05%, the material is considered an extremely active surface-tension-reducing agent.

Compound	Surface Tension in dynes/cm. at 25° C.		
	.25%	.10%	.05%
(1) Tributyl dodecyl phosphonium chloride...	30.6	34.5	34.5
(2) Tributyl octadecyl phosphonium bro- mide.....	25.3	25.8	27.3

TABLE 1

As previously mentioned, the bacteriostatic agents of the present invention are effective in controlling bacterial growth in the presence of detergents such as an Ivory brand neutral high grade toilet soap which is a mixture of alkali metal salts of fatty acids analyzing about 46 weight percent oleic and linoleic acid, about 14 weight percent stearic acid, about 30 weight percent palmitic acid and about 10 weight percent of lower fatty acids (myristic, lauric, etc.), and when incorporated in such a soap in a weight ratio of one part to 50 parts soap are effective in low concentrations (from about 1 to 100 p.p.m.) against an inoculum of a standard culture of *Micrococcus pyogenes* var. *aureus* (*Staphylococcus aureus*) of standard resistance in a Sabourard's dextrose agar medium.

Comparable effectiveness can also be obtained when using other soaps such as a Lux brand solid neutral white toilet soap (a mixture of alkali metal salts of fatty acids whose fatty acid content analyzes about 45% oleic and linoleic, about 30% palmitic acid, about 10% stearic acid and about 15% lower fatty acids) as well as anionic, nonionic and amphoteric synthetic detergents. Anionic surface active compounds can be broadly described as compounds which contain hydrophilic and lyophilic groups in their molecular structure and which ionize in an aqueous medium to give anions containing the lyophilic group. These compounds are usually the alkali metal salts of organic sulfonates or sulfates, particularly the sodium salts, such as alkyl aryl sulfonates (e.g. sodium dodecyl benzene sulfonate), sulfate of straight chain primary alcohols (e.g., sodium lauryl sulfate) and the like. Nonionic surface active compounds can be broadly described as compounds which do not ionize but acquire hydrophilic characteristics from an oxygenated side chain, usually polyoxyethylene, while the lyophilic part of the

molecule may come from fatty acids, phenols, alcohols, amides or amines. For example purposes only, the polyethylene oxide condensates of alkyl phenols (e.g., condensation product formed from 1 mole nonyl phenol and 10 moles ethylene oxide), the condensation products of aliphatic alcohols and ethylene oxide (e.g. condensation product formed from 1 mole tridecanol and 12 moles ethylene oxide) are suitable nonionic surface active compounds in practicing the invention. Amphoteric surface active compounds can be broadly described as compounds which have both anionic and cationic groups in the same molecule. Examples of such compounds include sodium N-methyl taurate and sodium N-coco beta amino propionate.

While a detergent composition of the present invention need contain only a detergent and the quaternary phosphonium halide, it will be appreciated that the incorporation in the mixture of additional ingredients commonly used with cleansing agents, such as perfume, builders (e.g., sodium tripolyphosphate) anti-redeposition agents (e.g., carboxymethylcellulose), brightening agents (e.g., fluorescent dyes) and the like, is contemplated as being within the invention.

A further understanding of the detergent compositions described herein and processes for preparing the compositions will be obtained from the following specific examples which are intended to illustrate this invention, but not to limit the scope thereof, parts and percentages being by weight unless otherwise indicated.

Example 7

A detergent composition is prepared formulated as follows:

Additive:	Parts
Soap comprised of:	
Sodium salts of fatty acids derived from coconut oil (primarily lauric acid) 15 to 20%; sodium salts of fatty acids derived from tallow (approximately 40% stearic acid, 30% oleic acid, and 30% palmitic acid) 80 to 85%	98
Tributyl dodecyl phosphonium bromide	2

The above composition is prepared by melting the soap in a suitable vessel at about 60 to 70° C. and adding the phosphonium bromide to the soap with agitation. The admixture is then poured into a suitable mold and allowed to solidify by cooling to room temperature (about 25° C).

Example 8

A liquid detergent composition is prepared formulated as follows:

Additive:	Parts
Water	46.1
Sodium carboxymethyl cellulose (95% by weight)	.5
Fluorescent dye	.025
Disodium acid pyrophosphate	5.0
Nonionic organic active (nonyl phenol-ethylene oxide condensate)	10.0
Maleic anhydride-ethylene copolymer	1.0
Tetrapotassium pyrophosphate	20.0
Potassium hydroxide (45% by weight)	6.7
Sodium silicate (Na ₂ O:SiO ₂ of 1:2) (44.1% by weight)	10.0
Tributyl dodecyl phosphonium chloride	1.0

The above composition is prepared by heating the water to about 60° C. and thereafter adding the above additives to the water in a mixer in their above listed order, each additive being added and mixed under high shear agitation over a period of about 1 to about 7 minutes while ensuring that the temperature of the mix does not exceed about 80° C.

Example 9

An antiseptic shampoo composition is prepared formulated as follows:

5 Additive:	Parts
Triethanol lauryl sulfate	60
Methyl cellulose	2
Propylene glycol	4
Potassium stearate	6
Water	130
Tributyl tetradecyl phosphonium chloride	2

The above composition is prepared by melting the potassium stearate at about 60 to 70° C. and adding thereto the triethanol lauryl sulfate, methyl cellulose, propylene glycol and tributyl tetradecyl phosphonium chloride until the mixture is well mixed and blended and thereafter adding the water in such a manner as to prevent aeration.

What is claimed is:

- 20 1. An antiseptic detergent composition consisting essentially of a detergent selected from the class consisting of soap and organic synthetic detergents selected from the class consisting of non-soap anionic, nonionic and amphoteric surfactants and at least an antiseptically effective amount of a quaternary phosphonium halide of the following formula

30 wherein R₁ is an aliphatic group containing from 6 to 24 carbon atoms; R₂, R₃ and R₄ are members selected from the group consisting of aliphatic groups, aryl groups, alkaryl groups, aralkyl groups, and alicyclic groups of from 1 to 12 carbon atoms; and X is a member selected from the group consisting of chloramine, bromine, and iodine ions.

35 2. An antiseptic detergent composition according to claim 1, wherein said quaternary phosphonium halide is present in amounts below about 50% by weight of said compositions.

40 3. An antiseptic detergent composition according to claim 2, wherein said detergent is soap.

45 4. An antiseptic detergent composition according to claim 2, wherein said detergent is an organic synthetic detergent selected from the class consisting of non-soap anionic, nonionic and amphoteric surfactants.

50 5. An antiseptic detergent composition consisting essentially of a detergent selected from the class consisting of soap and organic synthetic detergents selected from the class consisting of non-soap anionic, nonionic and amphoteric surfactants and at least an antiseptically effective amount of an unsymmetrical tetra alkyl phosphonium halide of the following formula

55 60 wherein R₁ is an alkyl group containing from about 8 to 18 carbon atoms; R₂, R₃ and R₄ are lower alkyl groups containing from 1 to 5 carbon atoms and X is a member selected from the group consisting of bromine and chlorine ions.

65 6. An antiseptic detergent composition according to claim 5, wherein said unsymmetrical quaternary alkyl phosphonium halide is present in amounts below about 50% by weight of said composition.

70 7. An antiseptic detergent composition according to claim 6, wherein said detergent is soap.

75 8. An antiseptic detergent composition according to claim 6, wherein said detergent is an organic synthetic

detergent selected from the class consisting of non-soap anionic, nonionic and amphoteric surfactants.

9. An antiseptic detergent composition according to claim 5, wherein said unsymmetrical tetra alkyl phosphonium halide is present in amounts from about .05% to about 10% by weight of said composition.

10. An antiseptic detergent composition according to claim 9, wherein said unsymmetrical tetra alkyl phosphonium halide is tributyl dodecyl phosphonium chloride.

11. An antiseptic detergent composition according to claim 9, wherein said unsymmetrical tetra alkyl phosphonium halide is tributyl dodecyl phosphonium bromide.
